FOREIGN PATENT DOCUMENTS

EP 0631948 4/1995

Primary Examiner — Marianne Pandozzi*(74) Attorney, Agent, or Firm* — Buche & Associates, P.C.; John K. Buche; Bryce A. Johnson(57) **CLAIM**

The ornamental design for a portable beverage brewing machine, as shown and described.

DESCRIPTION

FIG. 1 is a perspective view of a portable beverage brewing machine showing my new design;

FIG. 2 is a left side view thereof;

FIG. 3 is a right side view thereof;

FIG. 4 is a front view thereof;

FIG. 5 is a rear view thereof;

FIG. 6 is a top plan view thereof;

FIG. 7 is a bottom plan view thereof; and,

FIG. 8 is an exploded perspective view thereof.

The broken lines in the drawings depict portions of the portable beverage brewing machine that form no part of the claimed design.

1 Claim, 5 Drawing Sheets(56)
